UNITED STATES PATENT OFFICE.

EARL D. OLMSTEAD, OF PHILADELPHIA, PENNSYLVANIA.

MUSIC-ROLL CABINET.

1,368,192.

Specification of Letters Patent.

Patented Feb. 8, 1921.

Application filed July 9, 1920. Serial No. 395,042.

To all whom it may concern:

Be it known that I, EARL D. OLMSTEAD, a citizen of the United States, residing at Philadelphia, in the county of Philadelphia and State of Pennsylvania, have invented new and useful Improvements in Music-Roll Cabinets, of which the following is a specification.

The invention relates to cabinets for the accommodation of records of music and the like and has more particular reference to a cabinet for the accommodation of music rolls such as are usually employed in connection with player pianos and to this end the invention provides for a cabinet which will conveniently support the music rolls and the boxes in which they are usually contained in position so that they can be readily and easily discerned for the purpose of picking out a particular roll and readily removed, when it is desired to place them in use in the player piano.

The invention comprehends among other features a cabinet or stand which will present a neat and effective appearance, furthermore being of practical value in that it provides for the ready disposition of the music rolls so that their titles on the boxes can be readily seen, and a particular roll removed without disturbing the others.

In the further disclosure of the invention, reference is to be had to the accompanying drawings, constituting a part of this specification, and in which similar characters of reference denote corresponding parts in all the views; and in which,—

Figure 1—is a perspective of a cabinet or stand.

Fig. 2—is a plan view of one of the racks removed, and

Fig. 3—is a fragmentary vertical sectional view showing the manner of securing a rack in one of the posts.

Referring more particularly to the views the numeral 10 designates a stand in its entirety and which consists primarily of a frame 11 formed of uprights or posts 12, cross braces 13 and a bottom or shelf 14 which serves not only to strengthen the structure, but may be also employed for the accommodation of music rolls or for other purposes, a series of racks 15 being provided and forming the essential feature of the device. Each of the posts or uprights 12 is formed with a series of saw cuts 16 on inner faces thereof and each rack consists of a sin-

gle piece of metal in the nature of a flat plate or body and formed between its ends to provide an upstanding stop flange or rest 17 in the nature of a rib extending 60 entirely across the plate, the plate furthermore being cut to provide projections 18 extending from the sides with the upper edge 19 bent downwardly to form a stop flange as shown and the lower edge 20 also 65 bent downwardly for the sake of appearance and to do away with any sharp edge that ordinarily might present itself if the lower edge of the plate were not bent in some fashion.

In attaching each rack to the upright or post 12, it will be seen that each rack is arranged at an angle to the horizontal with the projections 18 fitting into the saw cuts 16 and with the ends of the stop flange 19 bearing against pieces of the posts adjacent those faces having the saw cuts therein so that the racks cannot slide out of the saw cuts because of their inclination on the frame. The cross rib or rest 17, it will be seen, provides a stop for the boxes 21 containing the music rolls which can now be readily disposed upon the racks with the ends of the boxes always visible so that the titles thereon can be easily read.

With the character of rack described, it will be seen that there is provided a simple construction which provides for the neat disposal of the music roll boxes in position where their titles can be easily read upon the ends of the boxes and that a single box can be readily removed without disturbing the others and it will of course be apparent that this stand or cabinet can be fashioned in any suitable manner to provide a neat and effective looking article of furniture.

Having described my invention, I claim—

A rack comprising a frame having uprights and inclined saw cuts in the inner faces thereof, and plates of sheet metal mounted between the uprights in inclined position and spaced relation and each having integral end projections slidable in the saw cuts and also having a forward pendent flange and an upwardly extending loop constituting a rest; said loop being located in spaced relation to the forward and rear edges of the plate and arranged longitudinally of the plate and in parallel relation to the forward side of the rack.

In testimony whereof I affix my signature.

EARL D. OLMSTEAD.
